UNITED STATES PATENT OFFICE

JAMES H. COATES, RALPH S. HOWE, AND WILLIAM F. COSTELLO, OF NEW BRITAIN, CONNECTICUT, ASSIGNORS TO THE NEW BRITAIN MACHINE COMPANY, OF NEW BRITAIN, CONNECTICUT, A CORPORATION OF CONNECTICUT

STOOL

Application filed January 16, 1929. Serial No. 332,838.

This invention pertains to furniture and more particularly to furniture made of sheet material. For purposes of illustration the invention is herein disclosed as embodied in 5 a stool intended for bathroom use. Except for minor features hereinafter specifically pointed out, this stool consists wholly of sheet metal parts permanently united, as by welding, the construction and arrangement of the 10 seat and legs with their connecting elements being such as to provide very great strength, stiffness, and rigidity without undue increase of weight.

The parts (particularly the legs) of articles of furniture made of sheet metal are almost always more or less resilient so that simple cross bars such as are used to connect the legs of wooden chairs, etc., have little effect in opposing relative movement of legs 15 at opposite sides of the chair or stool. Thus when such a sheet metal stool or chair is unsymmetrically loaded or subjected to lateral pressure, or when the stool rests upon an uneven surface, it is racked, becomes loose in its 20 joints, and may even collapse by bending of the parts or breaking away of welded or riveted joints. In accordance with the present invention the legs and seat are so constructed and relatively arranged as to provide 25 maximum strength and to distribute the load to the best advantage, while the legs (here disclosed as four in number) are united by a continuous bracing collar intermediate the upper and lower ends of the legs, and 30 which effectively opposes relative movement of adjacent or opposite legs so that the structure is as rigid as a wooden stool,—although much lighter, cheaper to make, and not subject to injury from heat or moisture.

40 In the accompanying drawings wherein one desirable embodiment of the invention is illustrated by way of example,

Fig. 1 is a side elevation of a stool of a type adapted for bathroom use;

45 Fig. 2 is a vertical section, to larger scale, substantially on the line 2—2 of Fig. 1 showing details of the seat member of the stool;

50 Figs. 3, 4, 5 and 6 are sections respectively on the lines 3—3, 4—4, 5—5 and 6—6 of Fig. 1, to larger scale;

Fig. 7 is a horizontal section, substantially on the line 7—7 of Fig. 1, to larger scale;

Fig. 8 is a section, substantially on the line 8—8 of Fig. 1, looking up toward the under side of the seat; and

Fig. 9 is a fragmentary section, substantially on the line 9—9 of Fig. 7.

In accordance with the preferred construction the seat 1 is substantially circular and is made from a disk of sheet metal of suitable 60 diameter and gage. This seat comprises a central portion 2 which is slightly depressed below the level of the rim portion 3, thus strengthening and stiffening the seat so that it does not tend to sag at its central portion. 65 Incidentally the shallow depression above this central portion 2 of the seat is well adapted to receive a layer 4 of heat insulating material, such for example as sheet cork, rubber, wood veneer, or the like, which may be secured to the part 2 by means of any suitable adhesive and which furnishes a seat surface of agreeable feel or appearance. If desired, the top of this veneer layer 4 may be flush with the upper face of the rim 3 or may 70 be slightly above or below such rim as is preferred.

The outer edge of the seat is turned down to form a depending marginal flange 5 whose lower edge, if desired, may be turned inwardly at 6 to provide a smooth finish. This seat member, with its marginal flange and its depressed central portion is exceedingly stiff and strong and capable of carrying a very heavy weight without bending or sagging, even though it be made of relatively thin material.

As here shown, the stool is provided with four legs tapering in width from their upper toward their lower ends, and adjacent legs 90 are arranged to diverge from their upper toward their lower ends. The upper end of each leg preferably consists of a substantially flat piece of the sheet material, as indicated at 8 in Fig. 8, and this flat portion is bent inwardly to provide the attaching flange 9. The attaching flanges are placed in contact with the under surface of the part 2 of the seat and are permanently attached thereto as by means of spot welding or the like,

indicated at 10. While welding is preferred as a means of uniting the legs to the seat, it is contemplated that other means, such for example as rivets, may be employed, although rivets or bolts are not so desirable since their heads are unsightly. As here shown the attaching flanges 9 of the legs are disposed wholly within and adjacent to the rib-like margin of the depressed portion 2 which distributes the load in the most effective manner to the several legs. As the upper ends of the legs are spaced inwardly from the flange 5, the latter forms a convenient means at all points for lifting the stool, and as the flange 5 is not called upon to carry the thrust of the legs, there is no tendency to deform it or bend it out of shape as commonly occurs when the legs are secured to the flange.

Immediately below the plane of the lower edge of the flange 5, the legs assume a section substantially such as shown in Fig. 3, comprising the two outer flange portions 11 and 12 disposed in planes at right angles to each other, and a diagonal connecting member 13. As above stated, the legs taper downwardly, and near their lower ends are of reduced section as illustrated in Fig. 6. Preferably the extreme lower end of each leg is bent into substantially annular form, as indicated at 14 (Fig. 5), and is thus well adapted to receive a tip member, such as a plug projecting upwardly into the end of the leg, or preferably an anti-friction cap 15 telescoping over the end of the leg, such cap being of rubber or the like.

The continuous bracing collar, as here disclosed comprises cross brace members 16 of sheet metal connecting adjacent legs. Preferably these brace members comprise vertical webs deeper at their ends than at their central portions, thus forming truss-like elements capable of supporting a substantial weight without bending, as for example if the foot of a person be placed upon the brace. The end portions of these braces are secured, as for example by welding, to the flange elements 11 and 12 of adjacent legs. Preferably the members 16, as shown in Fig. 4, are provided with inwardly directed integral flanges 17 disposed in a substantially horizontal plane, such plane being between the upper and lower ends of the legs and preferably somewhat nearer the lower ends than the upper ends.

In accordance with the present invention the ends of adjacent flanges 17 are united by means of connector members 19, Fig. 7. These connector members are of sheet metal and suitably shaped to fit within the hollow 10 of the legs and to overlap the ends of the flanges 17. The connector members are united to the flanges by welding or the like and thus unite the cross braces 16 to form a continuous rigid collar connecting all of the legs and effectively preventing relative move-

ment either of adjacent legs or of legs diagonally opposite. This continuous collar, which is substantially rigid both vertically and horizontally makes the stool extremely stiff and although the sheet metal employed may be of relatively thin gage, a stool thus constructed is as strong, stiff and rigid, and even more durable than a wooden stool of ordinary construction. At the same time it is lighter in weight than a wooden stool, or most other types of metal stool, it is cheaper to manufacture, and is not subject to injury from moisture or temperature change. The outer surface of the stool is smooth and free from projections, the corners are smoothly rounded and free from sharp angles which might cause injury to the person, and the entire surface of the metal may readily be covered with a protective lacquer or enamel to give a pleasing or ornamental appearance.

We claim:

1. A sheet metal stool having a seat and a plurality of legs, each leg being united at its upper end to the seat, the legs diverging downwardly, and a continuous collar uniting the legs intermediate their upper and lower ends, said collar comprising cross brace members uniting each adjacent pair of legs, each brace member having a substantially vertical web deeper at its ends than at its middle and having an inwardly directed horizontal flange, and connector members of sheet metal uniting adjacent ends of the horizontal flanges of the brace members, all of said parts being joined by welding.

2. A sheet metal stool having a seat and at least three legs each leg being united at its upper end to the seat by welding, the legs diverging downwardly, and means connecting all of the legs intermediate their upper and lower ends, such connecting means comprising vertical web portions, each web portion being united at its opposite ends respectively by welding to a pair of adjacent legs and being deeper at its ends than at its middle, the connecting means also comprising a continuous uninterrupted horizontal portion integrally united to each of the vertical web portions.

Signed by us at New Britain, Connecticut, this 10th day of January, 1929.
